2 SHEETS—SHEET 2.

UNITED STATES PATENT OFFICE.

STANLEY W. COONS, OF GERMANTOWN, NEW YORK.

AUTOMOBILE-RADIATOR.

1,286,237.

Specification of Letters Patent. Patented Dec. 3, 1918.

Application filed June 25, 1917. Serial No. 176,372.

To all whom it may concern:

Be it known that I, STANLEY W. COONS, a citizen of the United States of America, residing at Germantown, in the county of Columbia and State of New York, have invented certain new and useful Improvements in Automobile-Radiators, of which the following is a specification, reference being had therein to the accompanying drawing.

This invention relates to radiators for automobiles and the like, and has for its principal object the production of a simple and efficient radiator for cooling water passing through the water jackets of an engine, adapted to coöperate therewith.

Another object of this invention is the production of a simple and efficient means for constructing and producing an automobile radiator, whereby any of the parts thereof may be readily replaced should the same become rendered useless.

With these and other objects in view this invention consists of certain novel combinations and arrangements of parts, as will be hereinafter fully described and claimed.

This application is an improvement upon my previous patent bearing Number 1,166,327, and issued December 28, 1915.

30 In the accompanying drawings:—

Figure 1 is a front elevation of a portion of the radiator, parts thereof being broken away, and shown in section for the purpose of facilitating the illustration of the device.

35 Fig. 2 is a section taken on line 2—2 of Fig. 1.

Fig. 3 is a central longitudinal section through a portion of the radiator sections, the same being an enlarged section upon line 40 3—3 of Fig. 1.

Fig. 4 is an enlarged front elevation partly in section of the radiator tubes, showing the means for holding the same in proper spaced relation.

45 Fig. 5 is a side elevation of a portion of one side plate of the radiator tube, showing the filler carried in the tube thereof.

Fig. 6 is a section taken on line 6—6 of Fig. 5, both side plates of the radiator tube 50 being shown.

Fig. 7 is a side elevation of one of the filler plates used upon the end of the radiator.

Fig. 8 is a detail perspective of the filler plate shown in Fig. 5.

Fig. 9 is a detail perspective of one of the removable joint plates or sections adapted to constitute the upper and lower communicating means for the radiator.

Fig. 10 is a side elevation of a portion of the upper end of one of the radiator tubes, showing the manner of connecting the radiator tubes to the entrance casing of the radiator.

Fig. 11 is a vertical section through one of the connecting sections for connecting the vertical radiator tubes with the entrance casing, the same being a section taken on line 11—11 of Fig. 10.

Fig. 12 is a bottom plan view of the upper casing of the radiator.

By referring to the accompanying drawings by numerals, it will be seen that the radiator is placed within the usual radiating casing 1, and comprises an entrance casing 2, carried near the top thereof. This casing 2 is so arranged as to conform to the contour of the casing 1, and is provided with the usual cap 3, which cap is threaded into the upper threaded neck 4, of the casing 2. The casing 2 is provided with an entrance opening 5 into which entrance opening 5 the supply pipe 6 passes and this supply pipe 6 is braced by means of the bracing rod 7. This rod 7 is secured to the pipe 6 by means of an ear 8, the rod 7 passing back and being secured in any desired or convenient manner to the dash board, or other convenient place upon an automobile. The entrance casing 2 is provided with a plurality of joint connecting faces 9, each face having a plurality of securing apertures 10 formed therein, for the purpose of permitting the casing 2 to be supported upon a support of desired construction. The faces 9 are provided with suitable openings 11, for the purpose of registering with the apertures 12 formed in the caps 13, to insure thorough circulation of water through the several radiating sections to be hereinafter

described. The caps 13 are provided with reduced neck portions 14, at the bottom ends thereof over which neck portions fit the radiating tubings 15 shown clearly in detail in Fig. 1 of the drawings. Suitable bolts pass through the upper end of the caps 13, and through the apertures 10, for firmly holding the caps 13 in engagement with the faces 9 of the casing 2. It should be understood that the upper end of the tubings 15 fit over the reduced neck 14, as clearly shown in order to facilitate the attachment of the caps 13 to the tubings 15. It should be understood that the neck portions 14 are formed so as to constitute a reinforcement for the respective ends of the tubings 15, and that the respective ends of the tubings 15 are adapted to conform to the contour of the lower curved edge 16 of the cap 13 (Fig. 11). These caps 13 are provided with apertures 17 within the sides thereof, in order that a complete circulation of water may pass through the caps 13, and suitable apertures 18 are formed in the respective ends 25 of the caps 13, for the purpose of permitting the securing bolts 19 to pass therethrough, and firmly hold the caps 13 in engagement with and in nested relation with respect to the filler plates 20 and sections 21.

30 A bottom outlet casing 22 is adapted to be supported upon the frame 23 of the automobile or other motor vehicle, and this casing 22 is provided with suitable communicating means 24, similar to that described and illustrated with respect to the casing 2, for the purpose of forming a communication with the bottom caps 13 of the same construction as the top caps 13. It is thought unnecessary to go into detail in the 35 description of the bottom caps 13, in view of the fact that these caps are merely a duplicate of the structure described in detail in the specification and illustrated in Figs. 10 and 11 of the drawings.

40 45 It should be understood that a plurality of circulating sections 21 are placed between the caps 13 in the following way: A circulating section is first used, and between an abutting circulating section is placed a washer 25, which washer is of course provided with a suitable aperture for registering with the circulating section 21. The respective ends of the radiating tube are then fitted between two of the circulating sections 21, as shown in Fig. 1 of the drawing, thereby permitting complete circulation throughout a series of circulating sections and caps 13, as well as through the tube sections 11. A filler strip 20 is placed in 50 the upper end of each tube section, which fits between the circulating sections 21, and this filler plate is provided with a plurality of depending lips 26, which fit into the respective ends of the tube sections 11, for 55 permitting an efficient purchase of the tubes

upon the filler strips 20. The filler strips 20 are provided with suitable apertures 27 formed therein, through which the securing bolts 19 pass, for firmly connecting the circulating sections and filler strips together. 70 Each radiating tube 15 comprises a pair of plates, as shown clearly in Fig. 6, which plates have their abutting ends 28 soldered or otherwise secured together, for constituting an efficient water-tight seal. These radiating tube sections 15, are arranged in zig-zag relation throughout their entire length, and as shown in Fig. 4 a plurality of bracing plates are employed comprising a primary set of plates 30, and an auxiliary set 80 of bracing plates 31. The primary set of bracing plates are provided with inwardly enlarged, substantially V-shaped sockets 32, for receiving the bow portions of the radiating tubes or tube sections and the auxiliary 85 plates are also provided with V-shaped sockets 33, for the same purpose. Additional sockets 34 are formed transversely upon the auxiliary bracing plates 31, for receiving the substantially V-shaped web portions 90 of the primary bracing plates 30. By means of the device illustrated, especially in Fig. 4 and above described, it will be seen that the tube sections 11 will be efficiently braced and will be held against vibration. 95

As shown clearly in Fig. 1, of the drawings, it will be seen that the bottom casing or casting 22 is provided with outlet apertures 36 formed to receive the drain pipes 37 and these drain pipes 37 are provided 100 with lock nuts 38 for firmly holding the casing or casting 22 in engagement with the frame 23. Drain cocks 39 are carried by these pipes 37. It should be understood that the entire radiator may be easily 105 drained when so desired, through the medium of these drain pipes 37.

It should be understood that the top radiator sections are connected and held together by means of the transversely extending bolts 19, and these sections are gradually reduced in height when the ends of the radiator are arranged in step like relation as shown clearly in Fig. 1 of the drawings. The inner wall 40 of the tube section 41 is 110 provided with an opening at a point indicated by the numeral 40, and the outer wall of this top indicated by the numeral 41 is provided with an opening for forming a communication between the socket 42 and 115 socket 43. In like manner the radiator sections which are stepped downwardly at the respective ends of the radiator, may have a complete communication, as is illustrated in Fig. 13 of the drawings. 120

125 What is claimed is:

In a device of the class described, the combination with sections, tubes having their ends fitting between some of said sections, of a flat filler fitting in each end of 130

each tube, each filler including a closed top and vertical sides, each filler provided near its upper end with horizontal apertures, said sides also provided at their lower ends with 5 inwardly-extending horizontal feet with a space between said feet constituting an opening, and means in the horizontal apertures

of the filler and extending through said sections for securing said fillers between said sections, substantially as shown and de- 10 scribed.

In testimony whereof I hereunto affix my signature.

STANLEY W. COONS.
